2 Claims. (Cl. 72—88)

This invention relates to dies used for the production of certain types of screws by thread rolling wherein a blank is rolled between co-operating dies, the dies having rib and groove formations to produce the desired thread form on the blank.

The expression "screws" as used herein is to be considered in the generic sense as including drive nails, and the like, which have a "spaced-thread" form as defined hereinafter.

Certain screws, such as machine screws, have relatively sharp threads of fine pitch such that the die form for producing them by thread rolling consists of sharp ribs and sharp (generally V section) grooves but the type of screws with which this invention is concerned are those which are referred to in this specification as "spaced-thread" type and in which the convolutions of the thread are spaced apart by grooves, which may be flat bottomed, rounded, of generally U form, or otherwise "non-sharp," such that the corresponding die form, in the thread rolling operation, needs ribs of flat top, rounded, or other "non-sharp" form to produce these grooves.

Considering the type of machine which has a pair of flat dies which are reciprocated relatively to roll the blank therebetween, the form of the flat die used hitherto for producing spaced-thread screws has been such that the cross-section of the die changes in form between the starting end and the finishing end. Over the finishing end of the die the thread form thereon has grooves to produce the desired thread ribs on the blank, and flat top or other "non-sharp" ribs to produce the desired grooves on the blank, but at the starting end of the die the ribs have had to be made sharp in order to obtain an initial deformation of the metal of the blank under relatively low pressure. The sharp form of the ribs gradually flattens out along the length of the die until it merges into the flat top or other "non-sharp" form at the finishing end.

Also, to prevent skidding of the blank when it first enters between the dies it has heretofore been necessary to roughen the surfaces of the dies at the starting ends and this has usually been done by providing transverse serrations. These serrations, although considered essential, are a drawback because they interrupt the thread form on the die and can produce undesirable flaws in the finished thread on the blank.

The object of the invention is to provide improvements in the dies used for producing these spaced-thread type of screws by a thread rolling operation.

According to the invention I provide a die for use in producing a spaced thread type of screw wherein at the finishing end of the die the cross-sectional form is such as to provide ribs having crests which are of the desired flat top, rounded, or other "non-sharp" form and at the starting end of the die the cross-section provides ribs which are somewhat similar in section to those at the finishing end but each rib at the starting end has its crest interrupted to provide the desired degree of sharpness, the interruption decreasing along the length of the rib from the starting end to the finishing end of the die.

The interruption of the crest of each rib may be in the form of a groove or grooves of relatively shallow depth and the or each groove would be formed so that it de-

2

creases in depth as it progresses from the starting end of the die until it disappears completely at the position where the rib merges into the finishing end of the die.

The invention is illustrated in the accompanying drawings wherein:

FIGURES 1A and 1B are given as examples to show the form of thread on spaced-thread type screws.

FIGURE 2 is a diagrammatic illustration of a die according to the invention for use in a flat die type of thread rolling machine.

FIGURE 3 shows three fragmentary views showing the cross-section of the die form on the three lines A—A, B—B, D—D, in FIGURE 2.

FIGURE 4 shows three alternatives for the cross-sectional die form on the line A—A of FIGURE 2.

The spaced thread types of screws illustrated in FIGURES 1A and 1B each have thread convolutions 10 which are spaced apart by grooves 11 having flat, or substantially flat bottoms.

20 In the production of a self-tapping screw which has a relatively sharp thread form, such as that shown in FIGURE 1A, the form of the die 12 for producing such a screw is such that over the finishing section 13, the cross-section (see D—D in FIGURE 3) provides ribs 14 spaced apart by relatively deep grooves 15 which are such as to form the actual thread 10 while the ribs 14 have flat tops 16 and outwardly converging side faces 17 to produce the flat bottom grooves 11 between the convolutions of the thread 10.

30 At the starting end 18 of the die the cross-section (see A—A in FIGURE 3) is somewhat similar to that at the finishing end (section D—D) except that the flat top of each rib 14 is interrupted by a relatively shallow groove 19 which may be of part-circular section and which in effect produces two ridges 20 at the top of the rib thus creating a degree of sharpness and this groove 19 continues along the length of each rib but gradually decreasing in depth (see section B—B) until it disappears completely at the position where the rib runs into the finishing section 13 of the die.

35 The groove 19 may take various forms depending upon the degree of sharpness required, the nature of the material of the blank and the dimensions thereof, and instead of one groove there may be two or more grooves. Certain alternatives for the form of the groove 19 or grooves are shown in FIGURE 4. In the top view the groove 19 is of sharp V form but shallow as compared with the depth of the thread forming grooves 15.

40 In the view next below there are two quite shallow grooves 19a along the top of each rib separated by a fairly shallow ridge while in the bottom view there are two grooves 19b of more pronounced depth separated by a pronounced rib but of shallow depth as compared with the thread forming grooves 15. Such grooves 19, 19a, 19b, as shown in FIGURE 4 gradually decrease in depth along the length of each rib until merging into the finishing section of the die, as described above in connection with FIGURE 3.

45 One advantage of dies made in accordance with the invention as outlined above is that the provision of serrations or other form of roughening at the starting end 18 of each die can be eliminated or very substantially reduced as it is found that there is considerably less danger of skidding of the blank when first introduced between dies which have been formed in accordance with the invention. Consequently better threads can be produced on screws as the danger of flaws being produced is substantially reduced or eliminated.

50 Further it has been observed in practice that the thread form produced on the screw is generally better than that produced by dies used hitherto and it is considered that the presence of the interruption (the groove 19 or grooves)

in the crests of the ribs 14 at the starting end of the die in some manner gives a better control over the flow of the metal of the blank and appears to provide a more progressive gathering and disposing of the metal than does the conventional die as used hitherto. This has been observed particularly in connection with self-tapping screws where hitherto the grooves between the convolutions of the thread are not truly flat but have slight concavity, whereas, with dies in accordance with the invention, a more true flat-bottomed groove is obtained thus indicating that there has been a more faithful following of the contour at the finishing end of the die by the metal of the blank as it is flowing under pressure.

In applying the invention to a machine having a pair of flat dies one of which may be fixed while the other reciprocates, the invention is preferably applied to both dies. However, if greater economy is desired, the one die can be constructed in accordance with the invention while the other die may be formed so that it has a constant cross-sectional form from end to end, this form being the same as at the starting end of the die which is in accordance with the invention (i.e. section A—A), with the aforesaid interruptions or grooves 19 being continued at the same depth throughout the lengths of the ribs from end to end of the said other die. With this arrangement this latter die being of constant cross-sectional form, can be reversed end for end when any substantial wear has taken place along one side of the die so as to make more economic use of the whole of the die face. With such an arrangement the finishing end of the one die which has the flat top ribs and is constructed in accordance with the invention is the one which dictates the final form of the thread.

Also, although the invention has been particularly described in relation to flat dies, it may also be applied to machines wherein the blank is rolled between two or three co-operating rotary rolls each of which has a thread form on its circumference.

What we claim then is:

1. A die for use in rolling a thread upon a blank to produce a spaced thread type of screw having, on its blank engaging face, a thread form comprising alternate ribs and main grooves extending from the starting end to the finishing end of the die and wherein, at the finishing end of the die each rib has a crest which is of flat-top form and, at the starting end of the die, each rib has a form which is similar to that at the finishing end, but each rib at the starting end having its crest provided with at least one groove, extending longitudinally of the rib and of a depth which is relatively shallow as compared with the depth of the main grooves, such groove decreasing in depth from the starting end to the finishing end of each rib until it disappears at a position short of the finishing end of each rib.

2. A pair of dies for use in a flat die rolling machine, in which the dies are reciprocated relatively to one another, wherein one die is constructed in accordance with claim 1, the other die having on its blank engaging face, a thread form comprising alternate ribs and main grooves extending from the starting end to the finishing end of the die, and wherein each rib of such die has a form which is the same as the form of a rib at the starting end of the first mentioned die, with the crest of each rib provided with at least one groove extending longitudinally of the rib and of a depth which is relatively shallow as compared with the depth of the main grooves.
